UNITED STATES PATENT OFFICE.

CLARK J. SMITH, OF OTTUMWA, IOWA, ASSIGNOR TO THE HARDSCOG
WONDER DRILL COMPANY, OF OTTUMWA, IOWA.

ROCK-DRILL.

No. 812,375.

Specification of Letters Patent.

Patented Feb. 13, 1906.

Application filed August 7, 1905. Serial No. 273,125.

To all whom it may concern.

Be it known that I, CLARK J. SMITH, residing at Ottumwa, in the county of Wapello and State of Iowa, have invented certain new and useful Improvements in Rock-Drills, of which the following is a specification.

My invention relates to certain new and useful improvements in rock-drills, and it particularly seeks to provide a tool of this character so arranged that it can be mounted on an arm, column, or post and when set in position to drill or bore the hole it will not have to be changed in any way from the alinement of the hole in order to change the bits, thereby saving a considerable amount of time in changing bits.

Again, my invention seeks to provide a tool of this character in which means are provided for automatically feeding the drill or rock as fast as it cuts or bores the material, which feed is automatic in its operation and will adjust itself when drilling or boring in substances that are of variable hardness, and thereby relieves the operator of unnecessary labor of feeding the machine.

My invention also seeks to provide a tool of this character so mounted as to be capable of drilling at all angles and in which means are provided for removing the drill-casing and the operative parts of the drill proper from the support to enable the bits to be changed without altering the position of the support, so that when the parts are again assembled the drill will once more be in alinement with the hole, and thus avoid the necessity of repeated adjustments.

Generically my invention comprises a drill including a casing provided with an external threaded portion, a pneumatic hammer within the casing, a drill-receiving chuck carried by the casing, a supporting-casing or tubular member to receive the drill-casing, and a friction worm-gear mounted on the supporting-casing for coöperating with the threaded portion of the drill-casing, a second support for receiving the supporting-casing, a third support for receiving the second support, and a fourth support for receiving the third support, all being arranged so that the drill can be adjusted to any angle desired and after once adjusted will always be held in such position during changes of drills and during the operation of the machine.

With other objects in view than have here-

tofore been specified the invention comprises certain novel construction, operation, combination, and arrangement of parts, all of which will be first described in detail and then be specifically pointed out in the appended claims, reference being had to the accompanying drawings, in which—

Figure 1 is a perspective view of the invention as applied for use. Fig. 2 is a vertical longitudinal section thereof. Fig. 3 is a vertical cross-section on the line 2 2 of Fig. 2. Fig. 4 is a similar view on the line 4 4 of Fig. 2. Fig. 5 is a horizontal section on the line 5 5 of Fig. 2 looking in the direction of the arrow, the worm-gear being shown in plan. Fig. 6 is a cross-section on the line 6 6 of Fig. 2.

Referring now to the accompanying drawings, in which like numerals of reference indicate like parts in all of the figures, 1 designates the drill-casing, which is externally threaded, as at 1^a, and has an internal bore 1^b, in which the hammer-barrel 2 is tightly fitted. At its rear end the casing 1 is provided with a central threaded bore 1^c to receive the plug 3, which has a central hollow chamber 3^a and a flange 3^b, which abuts the end of the casing or barrel 1 of the drill. The plug 3 also has a rearwardly-extending portion 3^c, provided with an externally-threaded portion 3^d, and whose end 3^e is adapted to receive the crank or handle 4, which is secured thereto, as shown. The plug 3 has a plurality of radial apertures 3^f, which communicate with the chamber 3^a and with the outside of the plug.

Fitted on the extending or hub portion 3^c of the plug 3 is a loose collar 5, having a central internal chamber 5^a for coöperating with the apertures 3^f and an internally-threaded pipe-receiving portion 5^b to receive the pipe connection 6 of the air-supply pipe 7, which is controlled by the valve 7^a, as shown. On each side of the loose collar 5 a fiber washer 8 is placed on the hub or extension 3^c of the plug 3, and the collars 8^a and the collar 6 are held in position by the check-nuts 9, 9, threaded onto the threaded portion 3^d of the plug 3, as shown, it being understood that the collar 5 is so adjusted as to permit the barrel 1 and the plug 3 being rotated without rotating the collar 5.

The hammer-barrel 2, before referred to, has a chamber 2^a in the front thereof to re-

ceive the drill-chuck 10, in which the drill 11 is held, and the chuck 10 abuts the internal web 2^b of the barrel 2, which barrel 2 is also provided with internal webs 2^c 2^d and annular chambers 2^e 2^f 2^g 2^h, respectively. The rear end 2^m of the barrel is internally threaded, as at 2ⁿ, to receive the plug 12, as shown. The barrel 2 has an outer annular chamber 2ⁱ, which communicates with the rear portion 1^x of the chamber 1^b of the casing 1 through a series of ports or grooves 2^s in the barrel 2, as shown, and the said chamber 2ⁱ communicates with the interior of the barrel through the ports 2^t, as shown. Reciprocally mounted within the barrel 2 is the hammer-piston 13, which has the usual head 14 and an enlarged annular portion 13^a at the rear thereof, while a chamber 13^b is formed within the piston 13, as shown, and is open at the rear of the piston 13 to communicate with the chambers 2^e 2^f of the barrel 2, a series of radial ports 13^c being also provided for the same purpose, while a series of ports 13^d are arranged adjacent the head 14 and open up communication between the chamber 13^b and the chamber 2^e when the piston is at the forward limit of its stroke and permit the exhaust to pass from the chambers 2^e 2^f into the chamber 2^e, while the ports 13^d communicate with the chamber 2^e when the piston is at the rearward portion of its stroke to permit the working charge to enter into the chamber 13^b and the chambers 2^e 2^f to force the piston again forward.

The drill-chuck 10 has a series of annular longitudinal grooves or apertures, 10^a 10^b, which register with apertures 2^x of the web 2^b to permit the exhaust charge from the chamber 2^e to pass out to the atmosphere, it being understood that the working agent enters the chamber 1^x through the bore or chamber 3^a of the plug 3 from the chamber 5^a of the collar 5, to which it is admitted from the pipes 7.

15 designates what I term the "support-casing," which comprises an elongated tubular portion 15^a, having an internal bore 15^b of such a diameter as to permit the ready movement of the drill-casing 1 therethrough, and this bore 15^b is smooth and non-threaded. The casing 15 is also provided with a pair of upwardly-projecting ears 15^c 15^d, provided with bearing-apertures 15^d 15^d to receive the shaft 16, which carries the hand-wheel 17, by means of which the shaft 16 is turned. The shaft 16 is of such diameter as to snugly fit the bearing-apertures 15^d, so that it will not turn freely. Mounted on the shaft 16 to turn therewith and between the ears 15^c 15^d is a worm gear-wheel 18, having peripheral gear-teeth 18^a to mesh with the threaded gear portion 1^a of the drill-casing 1, and the gear 18 I shall hereinafter term the "friction worm-gear," as such gear is held from free turning motion by friction. Integrally formed with the casing portion 15 is a downwardly-project-

ing tubular shank 15^x, which is adapted to be received by the bearing portion 19^a of the double clamp member 19 and is tightly held in its adjusted position in such bearing portion 19^a by the clamping-bolt 19^b, as shown, thus permitting adjustment of the tool on an axis running through the shank 15^x.

The clamping member 19 is provided with a second clamping portion 19^c at right angles to the portion 19^a to receive the supporting member 20, to which it is clamped by the bolt 19^d, as shown, and which permits adjustment of the tool on an axis running through the supporting member 20.

The supporting member 20 forms a lateral projection from another clamping member 21, which has its clamping portion arranged to clamp onto a support 22 at right angles to the support 20 and is held on such support by the clamping-bolt 21^b, as shown, thus permitting an adjustment of the support on an axis running through the support 22.

By virtue of the several adjustments on the axis of the shank 15^x, the supporting member 20, and the supporting member 22 the tool 90 may be adjusted to drill at any angle desired, as will be readily understood by reference to Fig. 1 of the drawings.

So far as described the manner in which my invention operates will be best explained as follows: Proper adjustment of the tool is made on the various supports to bring the drill 11 at the proper angle, the casing 1 being at the limit of its rearward position. The stop-cock 7^a is then opened to allow the compressed air, steam, or other suitable working agent to enter the chamber 1^x, from whence it passes into the barrel 2 to operate the hammer-piston 13, which piston as it reaches the forward limit of its stroke impinges the drill 11 and drives it into the hole, the piston being reciprocated automatically by reason of the arrangement of the various inlet and exhaust ports, &c., as clearly understood by reference to the drawings, the rearward movement of the piston being gradually stopped before the forward motion begins, due to the air-cushion formed in the chamber 2^h. The forward motion of the piston as it strikes the drill 11 will cause the casing 1, with all of its carried parts, to be moved forward automatically to feed the drill forward into the hole as the same is being cut, it being understood that the force of the hammer 13 against the drill 11 is sufficient to turn the shaft 16 and the worm-gear 18 in the direction of the arrow *a* in Fig. 2. As the piston is gradually stopped on its rear movement by the air-cushion formed in the chamber 2^h, the backward stroke of the hammer-piston does not tend to feed the casing backward. The forward stroke of the hammer-piston being sudden and impacting causes such a jar as to force the casing forward. After the hole has been cut to the maximum length possible with the 130

length of the drill that is in the machine or it becomes necessary to change drills to insert a longer drill or to insert a sharper drill the operator turns the hand-wheel 17 in the 5 direction of the arrow in Fig. 1, which thereby moves the entire casing 1 and its carried parts rearwardly in the direction of the arrow *b* in Fig. 2 until it becomes entirely released from engagement with the gear 18, after which the 10 operator then draws the casing 1 entirely out of the supporting-casing 15, and a new drill can be then inserted into the chuck 10. After this is done the operator again inserts the drill into the casing 15 and moves the same 15 up until the drill has been inserted into the hole and is ready to continue cutting. The exact initial adjustment can be made by turning the crank 4 or by turning the hand-wheel 17.

20 From the foregoing it will be seen that the invention comprises a simple and effective construction of drill of the class described and in which means are provided for readily and effectively removing the drilling mechanism from its support to insert a new drill and replacing the same in exactly the proper position with respect to the hole without the necessity of realining the drilling mechanism, thus saving a great deal of time in changing 25 the bits and avoiding the necessity of readjusting the parts and obviating possible errors in such readjustments.

From the foregoing description, taken in connection with the accompanying drawings, 35 it is thought the complete construction, operation, and many advantages of my invention will be readily understood by those skilled in the art to which it appertains, and I desire to say that slight changes in the detailed construction, operation, and arrangement of parts may be made without departing 40 from the scope of the appended claims and the invention.

Having thus described my invention, what 45 I claim, and desire to secure by Letters Patent, is—

1. In an apparatus of the class described, a supporting - casing, a drilling mechanism supported therein and feedable therethrough, 50 means coöperatively connecting the supporting-casing and the drilling mechanism to permit the drilling mechanism being fed forward at each forward impulse of the drill-hammer, and means whereby said drilling mechanism 55 can be bodily withdrawn from said supporting - casing, substantially as shown and described.

2. In an apparatus of the class described, a drilling mechanism including a reciprocating 60 hammer and a longitudinal drill-casing, a supporting-casing for receiving said drill-casing, said drill-casing having an exterior thread, means whereby said drill-casing can be rotated on its longitudinal axis to feed the 65 same forward, means carried by said sup-

porting-casing for coöperatively engaging the threaded portion of the drill-casing to enable it to have a threaded connection with the drill - casing, and means whereby said last-named means can be released from operative 70 connection with the drill-casing to permit the drill-casing being drawn out of the supporting - casing, substantially as shown and described.

3. An apparatus of the class described, 75 comprising a drill including a casing and a reciprocating hammer operable therein, said drill-casing having an externally-threaded portion, a supporting-casing having an internal bore for receiving said drill-casing, a drill-casing-engaging member on said supporting-casing for engaging said threaded portion of the drill-casing to lock the same to the supporting-casing, means carried by the drill-casing whereby the drill-casing can be turned 80 on its longitudinal axis to feed the same, said drill-casing and said drill-casing-engaging member being so arranged as to permit the drill to be automatically fed forward on its longitudinal axis at each forward impulse of 85 the hammer, all being arranged substantially as shown and described.

4. An apparatus of the class described, comprising a drill including a drill-casing and a reciprocating hammer operable therein, 90 said drill-casing having an externally-threaded portion, a supporting-casing having an external bore for receiving said drill-casing, a drill-casing-engaging member on said supporting - casing for engaging said threaded 95 portion of the drill-casing to lock the same to the supporting-casing, means carried by the drill-casing whereby the casing can be turned on its longitudinal axis to feed the same, said drill - casing and said drill-casing-engaging 100 member being so arranged as to permit the drill-casing to be automatically fed forward on its longitudinal axis at each forward impulse of 105 the hammer, and means for moving said member carried by the supporting-casing to move the drill-casing along its longitudinal axis through the supporting-casing substantially as shown and described.

5. An apparatus of the class described, 110 comprising a drilling mechanism consisting of a drill-casing and a hammer mechanism reciprocally mounted therein, means for operating said hammer mechanism, a supporting-casing consisting of a longitudinal tubular member for receiving said drill-casing, said 115 drill - casing capable of having longitudinal movement through said supporting-casing, a screw connection between said supporting-casing and said drill-casing, means for turning said drill-casing on its longitudinal axis 120 to feed the same, and means for moving said drill-casing longitudinally through said supporting-casing, all being arranged substantially as shown and described.

6. An apparatus of the class described, 125

comprising a drilling mechanism consisting of a drill-casing and a hammer mechanism reciprocally mounted therein, means for operating said hammer mechanism, a supporting-casing consisting of a longitudinal tubular member for receiving said drill-casing, said drill-casing capable of having longitudinal movement through said supporting-casing, a screw connection between said supporting-casing and said drill-casing, means for turning said drill-casing on its longitudinal axis to feed the same, means for moving said drill-casing longitudinally through said supporting-casing, said drill-casing and said supporting-casing and their screw connections being arranged to permit automatic feed of the drill-casing forward through the supporting-casing at each forward impulse of the hammer without rotating the casing, substantially as shown and described.

7. An apparatus of the class described, comprising a drilling mechanism consisting of a longitudinal tubular casing, having an external thread, a hammer-barrel fitted with in said casing, a drill-chuck within said hammer-barrel at its forward end, a closure-plug within said hammer-barrel at its rearward end, inlet-apertures communicating with the interior of the hammer-barrel, and the interior of the drill-casing, exhaust-ports for the hammer-barrel, a reciprocating hammer within the hammer-barrel, means for admitting compressed air into the drill-casing, a handle member secured to the drilling-casing whereby the same can be turned on its longitudinal axis a tubular supporting-casing having a bore for receiving the drill-casing, a worm-gear mounted in said supporting-casing, and adapted to mesh with the thread on the drill-casing, a hand-wheel for turning said worm-gear, said worm-gear and said drill-casing being arranged to allow the drill-casing to automatically feed forward at the forward movement of the hammer, while simultaneously permitting the drill-casing to be turned on its longitudinal axis by means of the handle, all being arranged substantially as shown and described.

8. An apparatus of the class described, comprising drilling mechanism consisting of an elongated tubular casing having an external thread, a tubular hammer-barrel fitted within said casing, a drill-chuck within said hammer-barrel at its forward end, a closure-plug within said hammer-barrel at its rearward end, inlet-apertures connecting with the interior of the hammer-barrel and the interior of the drill-casing, exhaust-ports for the hammer-barrel, a reciprocating hammer within the hammer-barrel, means for admitting compressed air into the drill-casing, a handle member secured to the drill-casing whereby the same can be turned on its longitudinal axis, a tubular supporting-casing having a bore for receiving the drill-casing, a

worm-gear mounted in said supporting-casing and adapted to mesh with the threads on the drill-casing, a hand-wheel for turning the worm-gear, said worm-gear and said drill-casing being arranged to allow the drill-casing to be automatically fed forward by the forward movements of the hammer, while simultaneously permitting the drill-casing to be turned on its longitudinal axis by means of the handle, and means for mounting said supporting-casing to permit adjustment of the drilling mechanism with the longitudinal axis of the drill-casing at any angle substantially as shown and described. 70 75

9. In a rock-drill, a supporting-casing, a drill-casing, screw connections between the supporting and drill casings, and means whereby the drill-casing can be ejected from the supporting-casing without turning the same on its longitudinal axis. 85

10. In an apparatus of the class described, the combination with the drill-casing, a supporting-casing for receiving the drill-casing, of means for screwing the drill-casing through the supporting-casing, and means carried by the supporting-casing and co-operating with the drill-casing for permitting the drill-casing to be automatically fed through the supporting-casing in one direction by the impulse of the drill-hammer, substantially as shown and described. 90 95

11. In an apparatus of the class described, the combination with the drill-casing, a supporting-casing for receiving the drill-casing, of means for screwing the drill-casing through the supporting-casing, and means carried by the supporting-casing and co-operating with the drill-casing for permitting the drill-casing to be automatically fed through the supporting-casing in one direction by the impulse of the drill-hammer and means co-operating with said last-named means for moving the drill-casing through the supporting-casing in the direction of its longitudinal axis without turning the drill-casing substantially as shown and described. 100 105 110

12. An apparatus of the class described, the combination with the drilling mechanism including a drill-casing and a reciprocating hammer, of a supporting-casing adapted to receive said drill-casing, screw connections between said drill-casing and said supporting-casing, means carried by the drill-casing whereby the same can be turned on its longitudinal axis to feed it through the supporting-casing, means carried by the supporting-casing for permitting the drill-casing to be moved in the direction of its longitudinal axis through the supporting-casing without rotating the drill-casing, substantially as shown and described. 115 120 125

13. An apparatus of the class described, the combination with the drilling mechanism including a drill-casing and a reciprocating hammer, of a supporting-casing adapted to 130

receive said drill-casing, screw connections between said drill-casing, and said supporting-casing, means carried by the drill-casing whereby the same can be turned on its longitudinal axis to feed it through the supporting-casing, means carried by the supporting-casing for permitting the drill-casing to be moved in the direction of its longitudinal axis through the supporting-axis without rotating the drill-casing, and for permitting the drill-casing to be fed through the supporting-casing, by each forward impulse of the drill-hammer, independent of the rotation of the drill upon its longitudinal axis substantially as shown and described.

14. An apparatus of the class described, comprising in combination with a drilling mechanism including a drill-casing and a reciprocating hammer therein, of a supporting-

casing, means for feeding the drill-casing 20 through the supporting-casing, by rotating the same on its longitudinal axis and means for feeding the drill-casing through the supporting-casing without rotating the drill-casing on its longitudinal axis, substantially as 25 shown and described.

15. In a rock-drill, a supporting-casing, a drill-casing, connections between the supporting and drill casings whereby the drill-casing can be fed through the supporting-casing, and means whereby the drill-casing can be ejected from the supporting-casing without turning the same on its longitudinal axis. 30
